Primary Examiner — Cynthia Ramirez(74) *Attorney, Agent, or Firm* — Leydig, Voit & Mayer, Ltd.(57) **CLAIM**

I claim the ornamental design for a snow removal device, as shown and described.

DESCRIPTION

FIG. 1 is a perspective view of a snow removal device according to the present invention.

FIG. 2 is a front elevational view of the snow removal device of FIG. 1.

FIG. 3 is a left side elevational view of the snow removal device of FIG. 1.

FIG. 4 is a rear elevational view of the snow removal device of FIG. 1.

FIG. 5 is a right side elevational view of the snow removal device of FIG. 1; and,

FIG. 6 is a top plan view of the snow removal device of FIG. 1.
